Primary Examiner — Shannon W Morgan*Assistant Examiner* — Messina L Smith(74) *Attorney, Agent, or Firm* — Carter, DeLuca & Farrell LLP; George Likourezos, Esq.(57) **CLAIM**

The ornamental design for headwear, as shown and described.

DESCRIPTION

FIG. 1 is a bottom, rear perspective view of headwear showing the new design;

FIG. 2 is a rear view of the headwear of FIG. 1;

FIG. 3 is a front view of the headwear of FIG. 1;

FIG. 4 is a left side view of the headwear of FIG. 1;

FIG. 5 is a right side view of the headwear of FIG. 1;

FIG. 6 is a bottom view of the headwear of FIG. 1; and,

FIG. 7 is a top view of the headwear of FIG. 1.

The broken lines in the drawings depict portions of the headwear that form no part of the claimed design.

1 Claim, 4 Drawing Sheets(56)
